[57] CLAIM

The ornamental design for a joystick handle for electrical-hydraulic control systems, as shown.

DESCRIPTION

FIG. 1 is a side view of a joystick handle for electrical-hydraulic control systems, showing our new design;

FIG. 2 is a top view thereof;

FIG. 3 is a bottom view thereof;

FIG. 4 is a front view thereof;

FIG. 5 is a rear view thereof; and

FIG. 6 is a side view thereof as seen from the opposite side as FIG. 1.

*FIG. 1**FIG. 2**FIG. 3*FIG. 4

FIG. 5

FIG. 6
